UNITED STATES PATENT OFFICE.

JOSEPH E. STEINMEIER, OF NEW YORK, N. Y., ASSIGNOR TO WESTERN CLOCK COMPANY,
OF LA SALLE, ILLINOIS. A CORPORATION OF ILLINOIS.

DESIGN FOR A CLOCK-FRAME.

47,439.

Specification for Design.

Patented June 8, 1915.

Application filed March 30, 1915. Serial No. 18,197. Term of patent 7 years.

To all whom it may concern:

Be it known that I, JOSEPH E. STEINMEIER, a citizen of the United States, residing at New York, in the county of New York and State of New York, have invented a new, original, and ornamental Design for Clock-Frames, of which the following is a specification, reference being had to the accompanying drawing, forming part thereof.

The figure is the front view of a clock frame, showing my new design.

I claim:

The ornamental design for a clock frame as shown.

JOSEPH E. STEINMEIER.
